Patented Aug. 27, 1918.

Inventor

William E. White
By his Attorney
O. Elroy Edwards

UNITED STATES PATENT OFFICE.

WILLIAM ELLIOTT WHITE, OF GRAHAM, NORTH CAROLINA.

MITTEN.

1,277,015.

Specification of Letters Patent. Patented Aug. 27, 1918.

Application filed May 6, 1918. Serial No. 232,738.

To all whom it may concern:

Be it known that I, WILLIAM E. WHITE, a citizen of the United States, and a resident of Graham, county of Alamance, and State 5 of North Carolina, have invented a new and useful Improvement in Mittens, of which the following is a specification.

The object of my invention is to provide a mitten which will protect the wrist and 10 hand but leave all fingers free for any manual operations that may be required and to make this mitten in a form which will be cheap, durable and warm. These and other 15 objects are clear by my invention, one embodiment of which is hereinafter more particularly set forth.

For a more particular description of my invention reference is to be had to the accompanying drawings forming a part here- 20 of in which

Figure 1 is a front elevation of my im- proved mitten.

Figs. 2 and 3 are sectional views and taken 25 on the lines 2—2 and 3—3 of Fig. 1, look- ing in the direction of the arrows.

Throughout the various views of the drawings, similar reference characters designate similar parts.

My improved mitten 1 is composed of a

knitted fabric 2 which is double the length 30 of the mitten and is bent back upon itself and has its inner ends secured together by suitable stitches 3 as indicated in Fig. 2. To provide for the thumb, suitable regis- 35 tering slits are made and the walls of these slits are secured together by stitches 4. In the preferred embodiment of my invention, the stitches 3 and 4 are button-hole stitches which are made with an ordinary button- 40 hole sewing machine in the usual way.

This mitten, when made as above de- 45 scribed, is the same for either hand and may be worn by all who have to work in cold weather as railway mail clerks, street car conductors, factory hands and the like. The device is so simple that it may be easily washed from time to time and it may be made of wool, cotton or other suitable ma- 50 terial.

Having thus described my invention, what I claim is:

A mitten composed of a tube of knitted material, folded back upon itself so as to form a tube with double walls and stitches for holding the ends of the tube together 55 and registering slits with their edges se- cured together to form a thumb hole.

WILLIAM ELLIOTT WHITE.
